(57) CLAIM

The ornamental design for a product package, as described and shown.

DESCRIPTION

FIG. 1 is a right front perspective view of a product package showing our new design;

FIG. 2 is a front elevation view thereof;

FIG. 3 is a right side elevation view thereof;

FIG. 4 is a top plan view thereof;

FIG. 5 is a rear elevational view thereof;

FIG. 6 is a left side elevation view thereof; and,

FIG. 7 is a bottom view thereof.

The broken line showing of the inside product is for illustrative purpose only and forms no part of the claimed design.
